UNITED STATES PATENT OFFICE.

WILLIAM EVERETT VER PLANCK, OF ERIE, PENNSYLVANIA, ASSIGNOR TO GENERAL ELECTRIC COMPANY, A CORPORATION OF NEW YORK.

FUEL-PUMP FOR ENGINES.

1,116,959.

Specification of Letters Patent. Patented Nov. 10, 1914.

Application filed February 12, 1913. Serial No. 747,955.

To all whom it may concern:

Be it known that I, WILLIAM E. VER PLANCK, a citizen of the United States, residing at Erie, in the county of Erie, State 5 of Pennsylvania, have invented certain new and useful Improvements in Fuel-Pumps for Engines, of which the following is a specification.

The present invention relates to high pressure pumps for supplying fuel to internal combustion engines of the high compression type, and has for its object to improve the construction thereof.

For a consideration of what I believe to be novel and my invention, attention is directed to the accompanying description and claims appended thereto.

In the accompanying drawings is illustrated one of the embodiments of my invention wherein—

Figure 1 is a partial view in side elevation of a high compression engine having oppositely moving pistons and arranged to actuate the pump from one of the connecting rods; Fig. 2 is an enlarged view, chiefly in side elevation, of the pump; Fig. 3 is a view in front elevation and section of the pump; Fig. 4 is a plan view of the same, and Fig. 5 is a vertical section of the pump in 30 the plane of the plunger.

In Fig. 1, 6 indicates the cylinder of an internal combustion engine of any suitable type. As an illustration I have shown one having oppositely moving pistons mounted 35 in the same cylinder, one of which is connected by the main connecting rod 7 to the crank shaft 8 and the other to said shaft by the long side rods 9. Fuel is introduced into the cylinder at a point between the pistons by the injector or pulverizer 10. Fuel is admitted to the injector from the pump by the pipe 11 and blast air by the pipe 12. 40 13 indicates the pump which may be operated in any suitable way, but by preference is operated from one of the connecting rods, usually one of the side rods 9 for convenience. This results in a mechanical simplification of the engine which is highly desirable.

14 indicates a lever or member that is pivotally supported at one end and at the

other end is connected by a lever or member 15 to the side rod. To the lever 14 is connected a link 16, the lower end of which is pivotally connected to the rocker 17. The 55 rocker has a fixed pivot 18 and in moving back and forth alternately depresses the plunger of the pump 13 and permits it to rise under spring pressure as will be described later.

60 Referring to Fig. 5, the pump comprises a casing 20 containing a cylinder 21, the upper part of which rises vertically therefrom. Located inside of the cylinder is a liner 22 in which is snugly fitted the plunger 23, the latter having annular grooves to reduce leakage. Surrounding the cylinder is a housing 24 that has a finished bore of relatively large diameter to receive the cross-head or tubular member 25. By telescoping the pump and said member the total length of the apparatus is materially reduced. Between the cylinder and member 65 is a coiled compression spring 26 which moves the plunger upwardly on its suction 70 stroke. The lower end of the spring rests on a shoulder on the casing and the upper end engages a collar 27 that is positioned on the plunger by an enlarged head 28 having a well rounded top. The crosshead comprises 75 a hollow cylindrical part and a head formed integral therewith in which is seated a removable flat faced and shouldered plug 29 which engages the head 28 and transmits motion thereto. Above the first is a second 80 plug 30 of similar construction with which the roller 31, Fig. 2, on one end of the rocker 17 engages. It will be noted that the rocker, crosshead and plunger are mechanically 85 separate, that said crosshead is of relatively 90 large diameter and that the point of contact between the plug 29 and the head 28 is directly in line with the axis of the plunger. As a result of this the plunger is not subjected to side thrust which would very soon 95 wear the parts and cause excessive leakage, particularly in a pump adapted to work under high pressures such as 1000 pounds per square inch, as in the present case. There is very little side thrust on the cross- 100 head, but such as there is is amply provided for by the large bearing surfaces.

Furthermore, a side thrust on the crosshead cannot be transmitted to the plunger by reason of the fact that the flat faced plug 29 can move horizontally with respect to the 5 rounded head 28.

In the casing is a pair of discharge valves 32 and 33 in series relation and arranged to open outwardly by fluid delivered by the plunger. Between the valves is a coiled 10 compression spring 34 that acts to seat valve 32, valve 33 being held closed by the fluid under pressure in the conduit beyond. The valve 33 is located in a holder 35 which communicates with the pipe 11 leading to the 15 fuel injector 10, Fig. 1. The upward movement of the valve 33 is limited by a projection on the cover 36 and the latter and the holder are held in place by a strap 37 which engages the central part of the cover and is 20 secured to the casing by bolts.

The suction valve 38 is provided with an elongated stem having a cap at its lower end. The valve and cap are guided in the holder 39 which has cut away sides to permit fuel 25 to freely enter from the supply chamber 40. The holder has a peripheral shoulder that is seated on the casing and a hollow nut 41 secures the holder in place. In the supply chamber is a valve lifter comprising an arm 30 42 carried by a spindle 43 and an adjusting screw 44. The amount of fuel discharged by the plunger on each working stroke is determined by the time of closing of the suction valve with respect to the end of said 35 plunger stroke. In other words closing the suction valve earlier or later increases or decreases the amount of fuel passing the discharge valves. On the suction stroke of the plunger the valve opens freely to admit fuel 40 to the cylinder from the supply chamber and so long as it is held open on the discharge stroke the fuel merely flows back through it to the supply chamber. When the lifter below the valve releases it the fluid displaced 45 from the cylinder closes it and thereafter all of the fluid passes through the discharge valves.

Referring now to Figs. 2 and 3 the means for controlling the action of the suction 50 valve will be described. In so far as this particular feature of my invention is concerned it is immaterial how the pump is constructed or actuated. Mounted on the fixed fulcrum or spindle 43, which has suitable bearings in the lower part of the casing, is a lever 45 for moving the lifter into and out of engagement with the suction valve. This lever is connected to the crosshead or tubular guide 25 by the rod 46, so as to be 55 moved in synchronism with the plunger and the actuator or rocker 17. The object in pivotally attaching the upper end of the connecting rod 46 to the tubular member is to simplify the apparatus by avoiding extra

parts, to bring the parts into substantial alignment thereby reducing the space required and to cause the work performed by the rod to take place as nearly as possible in a straight line. If the valve lifter merely moved up and down and had exactly the 70 same travel all the time the amount of fuel discharged on each working stroke of the plunger would be constant. In order to regulate the effective discharge of fuel from the pump the rod 46 is arranged to slide on the 75 lever 45 toward and away from the spindle 43, which supports it and the lifter, thereby changing the amount of travel of the lifter. Between the rod and lever is a ball and socket 46^a to reduce friction. The valve lifter and 80 lever 45 must be so related to the valve and its seat that the valve is released and permitted to seat on each working stroke of the plunger for a greater or less portion thereof, depending upon the load. To this end a 85 means is provided for sliding the lower end of the rod which means comprises a lever 47 that is mounted on a spindle 48 and a link 49 between the lever and sliding rod 46. To the spindle 48 is connected another lever 50 90 which may be actuated by hand where manual control is desired or by the ordinary speed governor where automatic control is desired. As shown the lever is hand actuated and carries a spring pressed latch 51 for engagement with a toothed sector 52. The relation of the parts is such that as the lower end of the link is progressively moved away from the spindle 43 the amount of fuel delivered on each pump stroke is decreased. 100 When in the extreme outer position the suction valve may be held open during the entire working stroke. This forms a simple and effective means for shutting down the engine by cutting off the fuel supply to the injectors or pulverizers. On the other hand as the lower end of the sliding connecting rod is progressively moved toward the spindle 43 the amount of fuel delivered on each working stroke is increased. If desired the 105 rod can be moved to such a position that the lifter is moved out of the position where it can control the suction valve. Such a relation of parts is useful in starting where full supply of fuel is often desired. Intermediate positions of course result in varying amounts of fuel being delivered by the pump. 110

Referring more especially to Figs. 1 and 2 as the engine pistons move up and down motion is imparted to the members 14 and 15 by the connecting rod 9. As the rod moves upwardly the pivot 53 uniting the members is moved to the left and since the link 16 is connected to the upper member it is raised bodily as its pivot 54 is moved in the arc of 115 a circle. This results in raising the right hand end of the rocker and depressing the left together with the pump plunger and 120

crosshead or tubular guide 25 against the action of the spring 26, Fig. 5. On the downward movement of the rod 9 the pivot 54 moves in the opposite direction and the link 16 is depressed and the left hand end of the rocker elevated, the spring 26 causing the plunger and its crosshead 25 to follow and suck in a charge of fuel. To vary the amount of fuel delivered the lower end of the link 10 46 is moved in one direction or the other to satisfy the load requirements either by a speed governor or a manually actuated lever. Fuel from the pump flows through the pipe 11 to the injector from which it is introduced 15 into the engine in any suitable way, as by a blast of high pressure air admitted by the pipe 12.

In accordance with the provisions of the patent statutes, I have described the principle of operation of my invention, together 20 with the apparatus which I now consider to represent the best embodiment thereof; but I desire to have it understood that the apparatus shown is only illustrative, and that 25 the invention can be carried out by other means.

What I claim as new and desire to secure by Letters Patent of the United States is:—

1. In a pump the combination of a cylinder, suction and discharge valves therefor, a plunger, a tubular member telescoping with the cylinder, the head of which member rests on the plunger, a spring for moving the plunger in one direction, a rocker for moving said member and the plunger against the spring, and means for moving the rocker.

2. In a pump the combination of a cylinder, suction and discharge valves therefor, a plunger, a tubular member which surrounds 40 the plunger and one end of the cylinder, a compression spring which is located between the cylinder and said member for moving the plunger in one direction, and means for applying end pressure to the member for 45 moving the plunger against the action of the spring.

3. In a pump, the combination of a cylinder, suction and discharge valves therefor, a plunger, a casing for the cylinder, a housing 50 that surrounds the cylinder, a tubular member which rests on the top of the plunger, and is guided by the housing, a compression spring that tends at all times to move the plunger out of the cylinder and also to move said member, and means for moving the member and through it the plunger against the action of said spring.

4. In a pump, the combination of a cylinder, a plunger therefor having a rounded 60 head, a collar on the plunger under the head, a spring which engages the collar for moving the plunger on the suction stroke, a tubular member that surrounds the plunger and spring, a guide for the member, a means car-

ried by the guide which rests on said head, 65 and means for depressing the member and through it the plunger.

5. In a pump, the combination of a cylinder, valves therefor, a plunger, a crosshead that is in telescopic relation to the cylinder 70 and plunger, a means for moving the plunger on the working stroke, and a means for moving the plunger on its compression stroke which surrounds the cylinder and is situated between it and the crosshead. 75

6. The combination of an engine having a connecting rod uniting its piston and shaft and a fuel injector, with a pump for supplying fuel to the injector, a rocker for actuating the pump, a pair of pivotally united 80 members, one of which is pivotally attached to the rod, a fixed pivot for the other member, and a connection between the members and rocker for actuating it.

7. In a pump, the combination of a cylinder, suction and discharge valves therefor, a plunger, means for actuating it, a suction valve lifter, a lever attached thereto, a rod which is pivotally attached to a movable 85 part of the pump at one end and is in sliding engagement with the lever at the other, and means for sliding the rod on said lever.

8. In a pump, the combination of a cylinder, suction and discharge valves therefor, a plunger, means for actuating it, a suction 95 valve lifter, a lever attached thereto, a rod which is pivotally attached to a movable part of the pump at one end and is in sliding engagement with the lever at the other, a rock-shaft, and means for connecting the 100 shaft and rod for sliding the latter on the lever.

9. In a pump, the combination of a cylinder, suction and discharge valves therefor, a plunger, a tubular member, means for actuating the plunger through said member, a lifter for the suction valve, a lever attached thereto, a rod pivotally attached to the member at one end and in slidable engagement with the lever at the other, and means for 110 sliding the rod on the lever to control the action of the lifter on the suction valve.

10. In a pump, the combination of a cylinder, suction and discharge valves therefor, a plunger, means for actuating it, a suction 115 valve lifter, a lever attached thereto, a rod which is pivotally attached to a movable part of the pump at one end and is in sliding engagement with the lever at the other, a rock-shaft, means connected to the shaft 120 and rod for sliding the latter on the lever, and means for moving the rock-shaft.

11. The combination of an engine having a connecting rod between its shaft and piston, a pump for supplying fuel to the engine 125 said pump having a plunger and means for actuating the pump plunger from the connecting rod, said means comprising a mem-

ber pivoted to the connecting rod and a second member pivoted to the first named member.

12. The combination of an engine having a connecting rod between its shaft and piston, a pump for supplying fuel to the engine said pump having a plunger, and means for actuating the pump plunger from the connecting rod, said means comprising a mem-

ber having a fixed pivot, and a second member pivoted to the first named member and to the connecting rod. ¹⁰

In witness whereof, I have hereunto set my hand this 7th day of Feby., 1913.

WM. EVERETT VER PLANCK.
